Thomas C. Reed, Washington, D. C.

Application September 19, 1947, Serial No. 141,497

Term of patent 7 years

(Cl. D56—4)

To all whom it may concern:

Be it known that I, Thomas C. Reed, a citizen of the United States of America, residing at Washington, District of Columbia, have invented a new, original, and ornamental Design for Combination Cocktail Table, Radio and Phonograph Cabinet, of which the following is a specification, reference being had to the accompanying drawings, forming a part thereof:

Figure 1 is a perspective view of a combination cocktail table, radio and phonograph cabinet, embodying my new design.

Figure 2 is a top plan view thereof,
Figure 3 is a front elevational view of the same,
Figure 4 is a side elevational view thereof, and
Figure 5 is a rear elevational view of the same.

I claim:

The ornamental design of a combination cocktail table, radio and phonograph cabinet, as shown.

THOMAS C. REED.
